UNITED STATES PATENT OFFICE.

CARL HENRIK SCHAGER, OF STOCKHOLM, AND JOHANNES MAGNUS JONAS-
SON LUNDIN, OF WÄRTAN, SWEDEN.

LOCK FOR RAILWAY-SWITCHES.

SPECIFICATION forming part of Letters Patent No. 606,362, dated June 28, 1898.

Application filed August 27, 1896. Serial No. 604,139. (No model.) Patented in Sweden April 29, 1895, Nos. 6,971 and 7,196; in Norway November 22, 1895, No. 4,936; in France January 21, 1896, No. 253,356; in Hungary February 10, 1896, No. 5,469; in England March 27, 1896, No. 6,752; in Austria May 6, 1896, No. 46/1,798; in Switzerland May 12, 1896, No. 12,603; in Turkey May 30, 1896, No. 520; in Canada July 4, 1896, No. 52,824, and in Finland October 3, 1896, No. 648.

To all whom it may concern:

Be it known that we, CARL HENRIK SCHAGER, residing at Stockholm, and JOHANNES MAGNUS JONASSON LUNDIN, residing at Wärtan, Sweden, subjects of the King of Sweden and Norway, have invented a new and useful Improvement in Locks for Railway-Switches, (for which we have obtained patents in Sweden, Nos. 6,971 and 7,196, dated April 29, 1895; in Finland, No. 648, dated October 3, 1896; in Norway, No. 4,936, dated November 22, 1895; in Austria, No. 46/1,798, dated May 6, 1896; in Hungary, No. 5,469, dated February 10, 1896; in England, No. 6,752, dated March 27, 1896; in Turkey, No. 520, dated May 30, 1896; in Switzerland, No. 12,603, dated May 12, 1896; in France, No. 253,356, dated January 21, 1896, and in Canada, No. 52,824, dated July 4, 1896,) of which the following is a specification.

This invention relates to improvements in apparatus for operating and locking of railway-switches to the best advantage.

The object of the invention is to provide simple and reliable apparatus for operating and locking railway-switches, so as to obtain the advantages of the switch being rigidly locked when the signal shows "clear" for trains or cars coming from the outside toward the switch, while at the same time the construction is such that when the switch is not locked it may be easily opened by a train or car coming out on the track for which the switch is not laid without damaging the track or switch or getting derailed. The construction is also such that the switch may be equally well be operated at the place or at a distance, so that switching may be done out on the train-yard when no train is expected to come through the switch from outside; but the apparatus may be locked from a distance—for instance, the railway-station—to prevent its being manipulated when a train is expected. This has the advantage that the station-master may himself lock the switches and see that they are locked when trains are expected and release them afterward without needing to go out to the switch, while, on the other hand, the switching-hands may operate

the switches when it is allowed without going to the station.

The invention consists in the combination and arrangement of parts as hereinafter set forth.

In the drawings, Figure 1 is a plan view of the apparatus applied to a switch on a railway-track. Fig. 2 is an elevation endwise of the apparatus, and Fig. 3 is a partial side elevation. Figs. 4 to 8 are detail views of the lever mechanism.

Similar letters of reference indicate corresponding parts in the several figures.

Referring to the drawings, *a* represents a rod or bar connected to the movable switch points or rails and extending to one side under one of the fixed rails. Said rod is, outside the rail, provided with a tap *b*, provided with a friction-roller and running in a slot *c* in a cam-plate *e*, which in its turn runs in suitable guides *d* in a direction at right angles to the length of the rod *a*. Said cam-plate is preferably placed above the rod *a*, but may also be placed below the same, and the slot *c* runs obliquely against the direction of the length of the rod, so that by moving the cam-plate in the same direction as a track runs the rod *a* will, by means of said slot and tap, be forced to move in the direction of its length, whereby the switch will be operated. For moving the said cam-plate *c* a lever *f* is pivoted in a suitable chair fixed to the cross-ties and by means of a pulley *f'* and rod *f''*, connected to the said cam-plate, so that by moving the lever *f* over to one side or the other the switch may be operated at the spot. The said lever *f* is also, by means of ropes *e* and pulley *f'*, connected to another lever *m*, placed at a distance—for instance, at the depot—so that the switch may be also operated by means of the last-mentioned lever. The said rod *a* extends farther toward a vertical axle or shaft, which is held by suitable bearings in a post and may either on its top carry a signal-disk or by means of wire ropes *j'* be so connected to another similar rod *g'*, carrying a signal-disk, that they are both turned at the same time. At the bottom the said rod *g* is provided with

- a cam or hook *h*, which is so placed or arranged that when the signal shows "clear" it runs in either of two slots *i* in the end of said cross-bar *a*. Said slots are placed so that when the cam or hook *h* runs in one of them the points of the switch-rails are laid and locked for one track, and when the hook runs in the other the switch is locked for the other track. The signal is by means of ropes *j* connected with a lever for operating the same, which lever is placed beside the lever *m* for operating switch at a distance. The result of this arrangement is that the station-master at the depot may himself see that the switch is laid for the right track and thereafter lock the same by placing the signal to show "clear," whereupon the yardmen are unable to interfere with the switch or do any switching until the station-master (after the train has passed the station) unlocks the switch by moving the signal to show "stop." The last-mentioned position of the signal-disk is shown in the drawings by dotted lines.
- The before-mentioned lever *m* for operating the signal at the station is on one side provided with a shield *p*, Figs. 7 and 8, so fixed and placed that it displays different sides for the two different positions of the lever and switch. The side corresponding to the switch being laid for the main track may be painted or otherwise marked, for instance, "1", and the other side similarly painted or marked "2," so that by looking at the shield the station-master may ascertain for which track the switch is laid.
- The before-mentioned lever *k* for operating the signal is on one side provided with a shield *o*, protruding over the post *n*, in which the lever *k* is pivoted. Said shield is bent to a curve of the same radius as the circle in which it moves when the lever is operated, and the top of the post *n* is suitably painted or marked "Stop" on the part covered by the shield when the signal stands for "stop" and similarly marked "Clear" on the part covered by the shield when the signal stands for "clear." The station-master is thereby enabled to ascertain the position of the signal without being obliged to directly look at the same.
- The invention need not be carried out exactly as shown in the drawings. So, for instance, may the tap *b* and cam-plate *c* change places, as will be well understood by any person skilled in the art to which it appertains.
- The operation of the apparatus is obvious.

When a train is expected, the switch is laid for the right track by means of either levers *m* or *f* and the signal set to show "clear" and the switch locked by means of the lever *k*. Before the train arrives the station-master may by looking at the levers *m* and *k* himself ascertain whether the switch is laid for the right track or not and whether the same is properly locked and signal rightly set or not. After the train has passed the signal is placed to show "stop," whereby the switch is unlocked, so that the same may be shifted at the spot by means of the lever *f* or at the station by means of the lever *m*.

What we claim as our invention, and desire to secure by Letters Patent, is—

1. In apparatus for operating and locking of railway-switches the combination of a cross-bar connected to the switch-points, a cam-plate adapted to move the said cross-bar, a switch-lever connected to the said cam-plate, a second switch-lever connected to the first-mentioned switch-lever, a cam or hook connected to a signal and adapted to hold the said cross-bar in either of its extreme positions, when the signal shows "clear," and a lever for operating said signal, substantially as and for the purpose set forth.

2. In apparatus for operating and locking of railway-switches the combination of a cross-bar movable in the direction of its length and adapted to move the switch-points, a cam-plate movable in the direction of the rails and adapted to move the said cross-bar, a switch-lever adapted to move the said cam-plate, a second switch-lever provided with signs showing the position of the switch and by means of suitable transmissions, such as wire rope, connected to the first-mentioned lever, a cam or hook connected to a signal-disk and catching in suitable notches in the said cross-bar so as to hold the switch-point in either of its extreme positions, and a lever provided with signs showing the position of said signal-disk and connected so as to operate the same, as and for the purpose set forth.

In testimony that we claim the foregoing as our invention we have signed our names, in presence of two witnesses, this 30th day of December, 1896.

CARL HENRIK SCHAGER.

JOHANNES MAGNUS JONASSON LUNDIN.
